PROCESS OF SWEETENING PETROLEUM DISTILLATES

Minor C. K. Jones, Bound Brook, and Richard C. Brandon, Elizabeth, N. J., assignors to Standard Oil Development Company, a corporation of Delaware

Application October 29, 1941, Serial No. 416,963

9 Claims. (Cl. 196—33)

This invention relates to the art of sweetening petroleum distillates involving the dispersion of a metal sulfide, e. g., lead sulfide, in the sweetened petroleum distillate, and has the object of facilitating the separation and recovery of the metal sulfide from the sweetened distillate.

Sweetening treatments are used to improve odor, correct corrosion, and eliminate sulfur-containing compounds which have deleterious effects on the stability and combustion qualities of hydrocarbon oils. Mercaptans are the sulfur-containing impurities which are largely responsible for the need of sweetening petroleum distillates, and in a number of sweetening treatments, they are reacted with salts of metals, such as lead, copper, zinc, magnesium, sodium, calcium, and the like, forming metal sulfides which tend to remain suspended in the oils. The present invention is applicable to these treatments, particularly in so far as they form suspensions of metal sulfides which are not readily hydrolyzed and removed by washing with water.

The most common sweetening process is known as the doctor treatment. This treatment, and modifications thereof, involve the formation or use of metal sulfides which tend to remain suspended in the sweetened oil to some extent, thus requiring a water washing step and recovery of the metal sulfides from the wash water.

The doctor treatment consists in agitating a sour distillate (one containing mercaptans), with a controlled amount of sulfur and an alkaline sodium plumbite solution. The reaction results in the conversion of mercaptans to less objectionable organic disulfides and the formation of lead sulfide. Most of the lead sulfide formed is separated by settling from the treated oil but some remains suspended or entrained in the sweetened oil. Accordingly, this oil is washed with water to remove the remaining suspended lead sulfide.

With the procedure of washing hitherto used, it has been impractical to remove satisfactorily the suspended lead sulfide from the sweetened oil to the extent desired due to limitations of time, apparatus, and the amount of wash water; and as a result, substantial amounts of lead sulfide left in the oil annoyingly have settled out in storage tanks. Use of wash water in extra large quantities makes recovery of the metal sulfide more difficult, because a portion of the metal sulfide tends to remain in the water phase, and results in a greater loss of lead, excessive consumption of water and power, greater loss in hydrocarbon product, and troubles from pollu-

tion of streams or rivers by the waste water. Consequently, it is very important to improve the water washing procedure so as to obtain a more rapid separation of the lead sulfide with a restricted amount of water and apparatus.

In accordance with the present invention, certain organic substances, particularly high molecular weight proteins, which characteristically form mucilaginous colloids with water, are used effectively to expedite the separation of the metal sulfide, up to the last traces thereof, from a sweetened hydrocarbon oil in the washing step, and thereby leave a clear sweetened product.

For example, by admixing a small amount, e. g., about 0.25% by weight of gelatin or casein with a certain amount of wash water, the time for separation of lead sulfide from a sweetened naphtha was shortened to about 1 minute and less, whereas by omitting these agents, from about 25 to 50 times as much time was required for the separation.

The amount of these high molecular weight protein agents required for making a considerable increase in the separation rate is very small, being of the order of from about 0.05% to about 1% by weight of the water, and more beneficially in the range of 0.1% to 0.5%; therefore, they are used in an extremely small proportion with respect to the hydrocarbon liquid treated, since only about 5% to about 30% by volume of water is used on the basis of the hydrocarbon liquid subjected to washing.

The agents found to be useful in the manner described for improving the washing procedure vary to some extent in composition and in certain properties; hence, there is some variation in the convenience of their employment and in their relative effectiveness.

Gelatin, which behaves very satisfactorily, is a typical high molecular weight protein. It swells in cold water and dissolves on heating to form a viscous liquid, which on recooling, solidifies to a gel. However, dilute solutions used in this procedure are not particularly viscous. For example, using 10% by volume of wash water containing 0.25% by weight of gelatin for washing a sweetened naphtha containing a small amount of suspended lead sulfide following sweetening and settling, the last traces of lead sulfide were removed by this washing in about 1 minute.

Casein was used also with satisfactory results. Casein is the most important protein constituent of milk. It resembles other proteins, but contains a small amount of phosphorus. It is insoluble in water, but effective amounts of casein

were dispersed satisfactorily in the wash water with the addition of a small amount of an alkali, e. g., sodium hydroxide. Using 10% by volume of wash water containing 0.25% by weight of casein for washing a sweetened naphtha containing a small amount of suspended lead sulfide, following sweetening and settling, final traces of the lead sulfide were separated out by this washing in about 30 seconds.

In addition to the typical high molecular weight proteins mentioned, which characteristically form with water a mucilaginous mass or glue, there are a number of others having these characteristics which may be used, but which are ordinarily less available and more expensive.

The preferred types of agents for aiding separation of the suspended metal sulfide in the washing step are those that are stable under the treating conditions, are readily dispersed homogeneously or colloidal in the wash water before or during its contact with the hydrocarbon liquid, and which leave the washed hydrocarbon liquid in a neutral and purified condition.

For the purpose of illustration, a preferred embodiment of the invention will be described with reference to a doctor sweetening process.

In the drawing is shown a flow diagram for a continuous doctor sweetening plant in which the present process may be applied.

Referring to the drawing, a sour petroleum distillate to be sweetened is charged by inlet line 1 into mixer 2, equipped internally with orifice mixing plates 3. In this mixer, the sour oil distillate is intermixed and agitated with the doctor treating solution (alkaline sodium plumbite) entering the mixer from line 4. Generally, the sour oil entering the mixer contains the desired amount of added free sulfur.

From the mixer 2, the reaction mixture is passed by line 5 to the lead sulfide settler 6, in which lead sulfide settled to the bottom is withdrawn together with spent treating agent by line 7 for regeneration and further use.

Sweetened oil, from which most of the lead sulfide has been settled, is withdrawn from settler 6 by line 10 to the water washing tower 11 equipped with wash water inlet 12, pressure control outlet 13, spent wash water drain 14, and finished oil product outlet 15.

The spent wash water is delivered by line 14 to a water settling tank 15, equipped with a bottom drain 16 for removal of water substantially free of lead sulfide which may be recycled to wash tower 11, an intermediate take-off line 17 for removal of water containing a concentrated suspension of metal sulfide, and skimming line 18 for removal of surface layer of oil substantially free of lead sulfide.

The intermediate aqueous layer withdrawn by line 19 may be centrifuged for further concentrating the metal sulfide, which may be then subjected to regeneration.

Although the agents employed in accordance with the present invention are admixed preferably and most conveniently with the water before it is supplied to the wash tower 11 by inlet line 12, they may be injected separately at any suitable point to facilitate settling in tower 6 or to further facilitate concentration of the metal sulfide in the water settler 15.

The use of the settling agents herein described may be practiced in various modifications of the doctor treatment. They may be used where sweetening is conducted in a batch system. They may be employed in obtaining more rapid and

complete separation of suspended metal sulfide when lead sulfide is used by itself as a sweetening agent or with some other metal compound.

It is to be noted that the high molecular weight protein agents which were found satisfactorily effective are substantially insoluble in the hydrocarbon oils but have a certain amount of affinity for water. In general, they are neutral and non-ionic. Thus, the preferred agents, particularly of the gelatin type, are beneficially used in obtaining a neutral finished distillate satisfactorily free of the agent and metal salts.

In general, the washing treatment is carried out near atmospheric pressure ranging up to about 30 lbs./sq. in. gauge and at temperatures varying from about 30° F. to 120° F.

The protein agents described have been used to obtain the rapidly completed separation of metal sulfide from the sweetened distillate with about half the amount of wash water ordinarily used.

A further advantage with the separation agents of the protein type is that they may be used effectively to concentrate the metal sulfide in a relatively small aqueous layer between a substantially sulfide-free upper oil layer and lower body of water in a water settler, so that recovery of the concentrated metal sulfide is facilitated, the used wash water in the bottom layer is in suitable condition for recycling, and a good recovery of the hydrocarbon product from the spent wash water is obtained.

It is not intended that the invention be limited to the specific examples which have been given for the purpose of this illustration, but it is intended that all modifications coming within the spirit of the invention be included in the scope thereof as defined in the appended claims.

We claim:

1. In a process of sweetening hydrocarbon distillate oils containing mercaptans involving the dispersion of metal sulfides in the sweetened distillate product, the step of separating the last traces of said metal sulfides from the oils which comprises washing the sweetened oil with a small amount of a high molecular weight protein having affinity for water, mucilaginous colloid forming characteristics, and oil-insolubility.
2. In a process of sweetening a sour petroleum distillate by a doctor solution of alkaline sodium plumbite, the step of removing the last traces of lead sulfide from a sweetened oil which comprises washing the sweetened oil with water containing a small amount of gelatin dispersed therein.
3. In a process of sweetening a sour petroleum distillate by a doctor solution of alkaline sodium plumbite, the step of removing final traces of lead sulfide from the sweetened oil which comprises washing the sweetened oil with water containing a small amount of casein dispersed therein.
4. In a process of sweetening a petroleum distillate containing mercaptans with a compound of a metal which forms a suspension of metal sulfide difficult to remove completely from the distillate by water washing, the improvement which comprises incorporating into water used to wash out last traces of the suspended metal sulfide from the sweetened distillate about 0.05% to 1% of a high molecular weight protein, characterized by hydrocarbon-oil-insolubility and ability to form a gelatinous and mucilaginous mass in water.
5. The steps of washing out and recovering

final traces of suspended lead sulfide from a doctor sweetened petroleum distillate, which comprises washing said sweetened distillate with from about 5% to 30% by volume of water containing about 0.05% to about 1% by weight of a high molecular weight protein of a type effective to concentrate the metal sulfide in a relatively small aqueous layer between a substantially sulfide-free upper oil layer and a lower body of water, separating spent wash water from the distillate, said spent wash water containing lead sulfide and entrained hydrocarbons, settling said spent wash water in a settling zone, wherein three layers are formed comprising a bottom layer of water substantially free of lead sulfide and suitable for recycling as water wash, an intermediate aqueous layer containing suspended lead sulfide, and a top layer of hydrocarbons substantially free of lead sulfide, and separately recovering materials from each of said layers.

6. In a process of sweetening a naphtha distillate containing mercaptans whereby a small amount of lead sulfide remains suspended in the sweetened distillate, the improvement of removing final traces of the suspended lead sulfide by washing the sweetened distillate with water containing about 0.1% to 0.5% by weight of gelatin.

7. In a process of sweetening a naphtha distillate containing mercaptans whereby a small amount of lead sulfide remains suspended in the sweetened distillate, the improvement of removing final traces of the suspended lead sulfide by washing the sweetened distillate with water containing about 0.1% to 0.5% by weight of casein and a small amount of an alkali.

8. In a process of washing a sweetened naphtha distillate containing a small amount of suspended lead sulfide to remove final traces thereof from the distillate, the improvement which comprises washing said distillate with about 10% by volume of water containing about 0.25% by weight of gelatin and separating from said distillate the wash water containing last traces of lead sulfide removed in a period of about 1 minute.

9. In a process of sweetening hydrocarbon distillate oils containing mercaptans involving the dispersion of metal sulfides in the sweetened distillate product, the step of separating the last traces of said metal sulfides from the oils which comprises washing the sweetened oil with a small amount of a protein selected from the group comprising gelatin and casein.
